United States Patent [19]
Allender, Jr.

[11] **Patent Number:** **Des. 276,796**
[45] **Date of Patent:** **** Dec. 18, 1984**

[54] **PORTABLE ELECTRICAL RESISTANCE
SENSING WAND**

[76] **Inventor:** **David G. Allender, Jr., 1651 Parrott
Dr., San Mateo, Calif. 94402**

[*] **Notice:** The portion of the term of this patent
subsequent to Aug. 9, 1997 has been
disclaimed.

[**] **Term:** **14 Years**

[21] **Appl. No.:** **279,870**

[22] **Filed:** **Jul. 2, 1981**

[57] **CLAIM**

The ornamental design for a portable electrical resistance sensing wand, substantially as shown.

DESCRIPTION

FIG. 1 is a top and left front perspective view of a portable electrical resistance sensing wand showing my new design;

FIG. 2 is a bottom plan view thereof;

FIG. 3 is a top plan view thereof;

FIG. 4 is a left side elevational view thereof;

FIG. 5 is a right side elevational view thereof;

FIG. 6 is a front elevational view thereof;

FIG. 7 is a rear elevational view thereof.

The wands of FIGS. 1-3 and 6-7 are shown broken away for ease of illustration.

FIG _ 1**FIG _ 2****FIG _ 3****FIG _ 4****FIG _ 5****FIG _ 6****FIG _ 7**
